OUTLET RECEPTACLE SWITCH

Elmer J. Zelt, Fort Wayne, Ind., assignor to
 General Electric Company, a corporation of
 New York

Application June 1, 1938, Serial No. 211,156

8 Claims. (Cl. 200—51)

This invention relates to a convenience outlet or outlet receptacle in which a switch mechanism is provided for controlling an auxiliary electrical circuit other than that connected to the convenience outlet.

An object of the invention is in the provision of switch means applied to a convenience outlet so that as a plug cap is inserted into the outlet receptacle the switch will be operated to control an auxiliary circuit electrically connected to the switch means.

In the accompanying drawing Fig. 1 is a perspective view of a convenience outlet incorporating an auxiliary switch means; Fig. 2 is a modified form of the invention illustrating a modification of the switch structure; Fig. 3 is an end view partially in section of the device of Fig. 1, and Fig. 4 is an exploded view of the outlet receptacle contacts and switch-operating means.

Referring to the drawing, and more particularly to Figs. 1, 3 and 4, a convenience outlet is shown at 10 which in the form of the invention illustrated comprises a duplex receptacle. The convenience outlet is provided with the customary terminal screws 11 and is formed with a plurality of recesses 12 housing the receptacle contacts 13. The recesses 12 are open in front for the reception of a plug cap 14, while the rear of the recesses are closed by a plate 15 which may be formed of fibrous insulating material. In addition, the plate maintains the receptacle contacts 13 within the recesses in a manner well known in the art. The convenience outlet is provided with a mounting strap 15' which passes around the closure plate 15 as shown by Fig. 1 and maintains the plate and contact elements in assembled position. The structure thus far described comprises a convenience outlet of the type customarily employed in house wiring.

It is sometimes advantageous to employ an auxiliary circuit in connection with the wiring circuit of the convenience outlet to indicate whether or not the receptacle is being used or, in some cases, to control a source of current to the convenience outlet. According to the invention a switch means, which is operated by the insertion of a plug cap into the receptacle, is applied to the convenience outlet. By connecting the switch in the auxiliary circuit this structure constitutes a simple and reliable method of obtaining the results indicated above.

In the form of the invention shown by Figs. 1, 3 and 4 an insulating mounting plate 16 is placed at the rear of the convenience outlet overlying the mounting strap and closure plate and

is secured thereto by any suitable means such as a threaded stud 17 which may extend through the body of the convenience outlet. An opening 18 extends through the mounting plate 16, strap 15' and closure plate 15 and is disposed substantially in axial alignment with one of the contacts 13 of the receptacle contacts. Slidably mounted within the opening 18 is a pin 19 which likewise is disposed substantially in axial alignment with the contact 13.

Referring more particularly to Fig. 3, one end of the pin 19 cooperates with a switch means which in the form illustrated comprises a movable spring contact blade 20 having a contact 21 which engages a corresponding contact 22 mounted on a relatively stationary switch blade 23. The spring switch blade 20 is of sufficient strength normally to maintain the operating pin 19 completely within the opening 18 in convenience outlet so that the contacts 21 and 22 are separated and the switch means is normally in open position. In the normal position just described the end of the pin 19 rests within an opening 24 formed in a bent portion of the contact blade 13 and abuts a side of the blade 13 formed by the opening 24. This arrangement prevents the pin from being forced out of the convenience outlet by the spring blade 20 and maintains the pin within the opening 18 under all positions of the convenience outlet so that it is impossible for the pin to drop out of the convenience outlet.

As shown more particularly in Fig. 3 the pin 19 is adapted to be actuated by a plug prong 25 forming part of the plug cap 14. It will be apparent that as the plug cap is inserted within the convenience outlet the prong 25 will engage and be guided by the receptacle contact 13 and moving axially thereof will make contact with the actuating pin 19 and move it to a switch-operating position such as shown in Fig. 3. The length of the contact pin 19 is so proportioned in relation to the standard length of the plug prong 25 that a firm contact pressure is maintained between the contacts 21 and 22 as the switch is closed the contact blade 23 being flexed slightly in closed position.

According to the form of the invention illustrated a separate switch means and switch-operating mechanism is located in the rear of each of the receptacle outlets of the duplex convenience outlet. While such a structure has been illustrated in Figs. 1 and 2 it will be apparent that the switch means might be equally as well adapted for application to a single convenience outlet, only.

In the form of the invention shown by Fig. 1 the movable switch blades 20 are interconnected by a jumper strip 26 which is secured to the base by means of a screw 27 which also serves the purpose of retaining a terminal lug 28 on the base in electrical connection with the switch blades. The flexible blades 20 are seated within grooves 29 formed in the base plate 16 and are fastened to the plate by means of screws 30. 5 The switch blades 23 extend to a common terminal point where they are secured to the base by means of a screw 31. A terminal element 32 is likewise secured to the base by the screw 31 to provide an electrical connection to the spring blades 23. In order to space the contact 22 from the contact 21 the switch contact blades 23 are mounted upon a projection 33 upstanding from the base of the mounting plate. It will be apparent from this construction that the terminal elements 28 and 32 serve for electrical connection to either of the two switch means, and thus it is unnecessary to provide separate terminal members for the respective switch structures. 10

One use of the invention is with a signal lamp 25 to indicate whenever the convenience outlet is being used. In such cases the terminal elements 28 and 32 may be connected in series with a current source and an indicating lamp, so that as a plug cap is inserted in either one of the outlet 30 receptacles the corresponding switch is operated to control the current to the indicating lamp.

In another use of the invention the switch means may be used for controlling the supply of current to the receptacle contacts 13. In such 35 cases the switch terminal elements 28 and 32 would be connected to control a source of current supply which, in turn, would be connected with the terminal screws 11 of the convenience outlet so that as the plug cap is inserted within the 40 convenience outlet the switch means would be closed to cause energization of the receptacle contacts 13. Inasmuch as the pin 19 is formed of insulating material, there is no electrical interconnection between the switch means and the 45 contact blade 13. The form of the invention shown by Fig. 2 is similar to that shown by Fig. 1 with various modifications in the switch structure. The duplex convenience outlet 40 is of substantially the same form as that shown in 50 Fig. 1, and is provided with terminal screws 41 and a mounting strap 42. The plate 43 is mounted on the rear of the convenience outlet by means of a bolt 44 and is adapted to provide a mounting surface for a switch means.

The switch means is operated in the manner 55 aforementioned employing the structure shown by Fig. 3. It constitutes the movable switch blades 45 having the contacts 46 cooperating with the opposed contacts 47 mounted on the contact 60 blades 48. The movable spring contact blades 45 are bent at an angle and are secured to the end of the mounting plate 43 by means of screws 49. Heavy metal caps 50 overlie the bent-over 65 portions of the contact blade and aid in maintaining the blades rigidly mounted upon the mounting plate. A jumper 51 interconnects the two contact blades 45 and a terminal element 52 is connected to one of the mounting screws 49 to provide a terminal for the contacts 46.

70 Each of the relatively fixed contact blades 48 is mounted upon a lug 53 upstanding from the base of the mounting plate, so that the contact 47 is spaced from the contact 46 in normal position. The ends of the contact blades are bent 75 at right angles and are held against the end of

the mounting plate by means of the heavy metal caps 54 overlying the bent-over portions of the contact blades. The caps and blades are secured to the base by means of screws 55, and a jumper 56 electrically interconnects the contact blades, 5 while the terminal element 57 provides a means of electrical connection to the contacts 47.

The convenience outlet shown by Fig. 2 has all the advantages above enumerated in connection with the form of the invention shown by Fig. 1 and, in addition, employs the caps 50 and 54 which aid in securing the contact blades to the base and provide a rugged construction.

In both forms of the invention the switch means is of simple construction yet positive in action. No separate operating means for the switch is necessary because the insertion of a plug cap into the receptacle serves to operate the switch mechanism. No great change is required in the standard convenience outlet because the switch mechanism and support is readily secured to the back of a convenience outlet.

What I claim as new and desire to secure by Letters Patent of the United States is:

1. In combination, a body comprising a convenience outlet having receptacle contacts therein, contact means mounted on said body having a movable operating member and an operating element adjacent said receptacle contacts and cooperating with said movable member, said operating element being engaged by the prongs of a plug cap inserted in said convenience outlet for operation of said contact means.

2. In combination, a body comprising a convenience outlet having receptacle contacts, contact means mounted on said body having a movable operating member and an axially movable pin in alignment with said receptacle contacts and cooperating with said movable member, said pin being engaged by the end of one of the prongs of a plug cap inserted in said convenience outlet for operation of said contact means.

3. In combination, a body comprising a convenience outlet having receptacle contacts, a pin 45 of insulating material slidably disposed in said body in substantially axial alignment with one of said contacts, and contact means mounted on said body having a movable member cooperating with said pin, said pin being engaged by a prong 50 of a plug cap inserted in said receptacle contacts and being axially movable by said cap for operation of said movable contact member.

4. In combination, a body comprising a convenience outlet having receptacle contacts, a plate of insulating material mounted on the base of said body, contact means including a flexible blade member mounted on said plate and a pin 60 slidably mounted in said plate, one end of said pin engaging said flexible blade member and the other end of said pin extending into said convenience outlet to a point adjacent one of said receptacle contacts and in axial alignment therewith.

5. In combination, a body comprising a convenience outlet having receptacle contacts, a plate of insulating material mounted on the base of said body, contact means including a flexible blade member mounted on said plate and a pin 70 slidably mounted in said plate, one end of said pin engaging said flexible blade member and the other end of said pin extending into said convenience outlet to a point adjacent one of said receptacle contacts and in axial alignment there- 75

with, said one contact being provided with an opening to receive said other end of the pin to retain the pin within said convenience outlet.

6. In combination, a body comprising a duplex convenience outlet receptacle having pairs of receptacle contacts, elements movably mounted in said body, one disposed adjacent each pair of receptacle contacts, pairs of cooperating contact elements mounted on said body, one pair coacting with each of said elements, and means electrically connecting the respective contact elements of each pair.

7. In combination, a body comprising a duplex convenience outlet receptacle having pairs of receptacle contacts, pins of insulating material slidably mounted in said body one disposed in

line with one of the contacts of each pair of contacts, pairs of cooperating contact elements mounted on said body, one pair coacting with each of said pins, and means electrically connecting the respective contact elements of each pair.

8. In combination, a body comprising a convenience outlet having receptacle contacts therein, contact means mounted on said body having a movable member, and an operating element of insulating material cooperating with said movable member, said operating element being moved by insertion of a plug cap in said convenience outlet for controlling said contact means.
